DESIGN FOR A FAMILY ALTAR.

SPECIFICATION forming part of Design No. 20,492, dated January 27, 1891.

Application filed December 12, 1890. Serial No. 374,491. Term of patent 7 years.

To all whom it may concern:

Be it known that I, GEORGE SHICKLUNA, a subject of the Queen of Great Britain, residing in the city of St. Catharines, in the county of Lincoln, in the Province of Ontario, have invented and produced a new and original Design for Family Altars, of which the following is a specification, reference being had to the accompanying drawing, forming part thereof.

The figure is a perspective view of my newly-designed altar.

The leading feature of my design consists

of a peculiarly-shaped altar, illustrated in the accompanying drawing, the base of which rests upon a rectangular stand.

Referring to the drawing, 1 indicates the stand on which sits the base 2 of the altar 3.

I claim as my invention—

The design for an altar, as herein shown and described.

Toronto, November 28, 1890.

GEORGE SHICKLUNA.
